CLAIM

The ornamental design for a handle for communication antenna as shown and described.

DESCRIPTION

FIG. 1 is a perspective view of a handle for communication antenna showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the handle for communication antenna of FIG. 1 combined with a communication antenna; and,

FIG. 10 is another perspective view thereof.

The dashed broken lines illustrate portions of the handle for communication antenna that form no part of the claimed design.

1 Claim, 7 Drawing Sheets
